UNITED STATES PATENT OFFICE.

MONTAGUE WILLIAM TUTT, OF LONDON, ENGLAND, ASSIGNOR OF ONE-HALF TO
HULBURD ENGINEERING COMPANY, LIMITED, OF LONDON, ENGLAND.

FORCE PUMP.

1,413,205.

Specification of Letters Patent. Patented Apr. 18, 1922.

Application filed July 22, 1921. Serial No. 486,800.

(GRANTED UNDER THE PROVISIONS OF THE ACT OF MARCH 3, 1921, 41 STAT. L. 1313.)

To all whom it may concern:

Be it known that I, MONTAGUE WILLIAM TUTT, a subject of the King of Great Britain, residing at St. Benet Chambers, Fenchurch Street, London, England, have invented new and useful Improvements in Force Pumps, (for which I have filed an application in Great Britain July 6, 1920, No. 157,692,) of which the following is a specification.

This invention relates to force-pumps for compressing air or gas and feeding or displacing liquids, of the kind wherein the pump body or cylinder is provided with two 15 pistons or plungers differentially movable in the same direction, between which the charge is compressed, the rod of one plunger extending through the rod of the other plunger, the object of the invention being to provide an improved pump of this type in which the usual suction and back-pressure or non-return valves are dispensed with.

According to the invention the improved pump comprises a cylinder having inlet and 25 outlet ports and a pair of plungers designed to be reciprocated in the said cylinder, the suction and compression space being provided between the said plungers. For this purpose the outer or upper plunger is maintained stationary for a portion, said one third, of each stroke whilst the lower or inner plunger is moving to draw in a charge through the inlet port. The two plungers then move together for the remaining portion of the stroke which brings the induced 35 charge opposite the outlet port. On the return stroke the outer or upper plunger is again held stationary for the first portion of the stroke, whilst the lower or inner plunger is drawn towards it to expel the charge 40 through the outlet port after which the two plungers move together for the remaining portion of the stroke when the operation begins de novo.

To operate the plungers I advantageously make use of the following arrangement, that is to say, the rod of the inner or lower plunger is reciprocated by a cross-head actuated by a crank on a crank-shaft which also carries a cam-plate rotating therewith, the said cam-plate having two cam surfaces diametrically opposite to one another which bear 50 against a roller attached to the upper or

outer plunger, thereby holding the said plunger stationary for the periods required. 55 The downward or inward movement of the outer or upper plunger is positively effected by an extension piece on the cross-head, whilst the return movement thereof is effected by the inner or lower plunger. 60

The pump may be either of the single acting type or of the tandem type or in the form of two sets of tandem pumps placed side by side or two sets of four pumps may be arranged one on each side of the centre 65 line of the crank-shaft, all the plungers being controlled by a single crank and cam.

To enable the invention to be fully understood, I will describe it by reference to the accompanying drawings, in which:

Figures 1, 2, 3, 4 and 5 are sectional elevations of a single-acting pump, constructed according to the invention and shewing the parts in the different positions they occupy during a complete stroke of the plungers, 75 and

Figure 6 is a sectional view illustrating a multiple double-acting pump.

a indicates the upper or outer plunger, *b* the lower or inner plunger and *c* the cylinder in which the said plungers are reciprocated. *e* is the inlet port to the cylinder *c* and *f* the outlet or discharge port therefrom. *g* is the rod of the inner or lower plunger *b*, the said rod passing axially through the 85 plunger *a* and *h* is the cross-head to which the outer end of the rod *g* is attached. This cross-head *h* is reciprocated by means of a slide-block *o* which moves in a slot *p* in the said cross-head *h*, the said block *o* being carried by the crank-pin *n* of the crank-shaft *n*. *d* is the extension piece provided on the cross head *h* for positively actuating the plunger *a*. 90

m indicates the cam-plate which is secured 95 to, so as to rotate with, the crank-shaft *n* and *k* and *l* are the two cam surfaces provided thereon, these two surfaces being curved to arcs of circles concentric with the crank-shaft. *j* is the roller which is attached to the outer end of the plunger *a* the said roller coating with the cam surfaces.

The plungers *a* and *b* and the plunger rod *g* are provided with peripheral packing grooves *i* and the plunger *a* is prevented 105 from rotating in the cylinder by means of

the longitudinal groove *r* with which engages a set-screw *q* projecting inwardly from the cylinder wall.

The pump operates as follows, that is to say, at the beginning of a stroke the parts are in the position shewn in Figure 1, the inner end of the plunger *a* being approximately coincident with the outer edge of the inlet port *e* and the plunger *b* being in contact with the plunger *a*. In this position of the parts the roller *j* is just in contact with the front end of the inner surface of the cam *k*. When, now, the crank-shaft *n*¹ rotates in the direction of the arrow the plunger *b* is moved inwards, the plunger *a* being held stationary by the cam *k* and is so held until the said cam has passed out of contact with the roller *j* during which period the movement of the plunger *b* has drawn a charge through the inlet *e* into the space formed between the plungers. This position of the parts is shewn in Figure 2 in which the extension piece *d* of the cross-head is in contact with the outer end of the plunger *a* so that for the remaining portion of the stroke the two plungers move together into the position shown in Figure 3 in which the inlet port *e* is completely closed by the plunger *a* and then into the position shewn in Figure 4 in which the space between the plungers is fully opened to the outlet port *f* and the roller *j* has made contact with the outer surface of the cam *l*. The continued rotation of the crank-shaft *n*¹ then moves the plunger *b* whilst the plunger *a* is held stationary, so as to expel the charge through the outlet port *f*. This relative movement of the plungers continues until the plunger *b* contacts with the inner end of the plunger *a* at which point the cam *l* leaves the roller *j* as indicated at Figure 5. In this position the plunger *b* completely closes the outlet port *f*. For the remaining portion of the stroke the two plungers move together until the cam *k* again engages with the roller *j* when the operation begins de novo.

In Figure 6 I have illustrated the application of the invention to a tandem pump formed of four double-acting pumps. In this construction the operation of which is identical with that shewn in Figures 1 to 5 each cylinder is provided with one plunger *b* which acts in conjunction with a pair of plungers *a* and all four plungers *b* are connected to and operated by a common cross-head *h* whilst the plungers *e* are controlled by a single cam-plate *m*. The inlet ports *e* of each unit may be coupled together as also may the outlet ports *f* thus providing a set of four double acting pumps instead of right separate pumps. In this arrangement it will be noticed that the plungers *a* are operated entirely by contact with the plungers *b*.

Claims.

1. A force pump comprising a cylinder having inlet and outlet ports, a pair of plungers reciprocable therein and means for retaining the upper or outer plunger stationary for a portion of the inward and outward strokes and for moving the said plungers together for the remaining portions of the strokes so as to draw in a charge between the plungers and expel it therefrom, the movement of one plunger being effected by the movement of the other plunger. 70

2. A force pump as claimed in claim 1, wherein the rod of the inner or lower plunger extends through the upper or outer plunger and is reciprocated by a crank-shaft which carries a cam-plate having two cam surfaces designed to engage and hold the upper or outer plunger, the inward and outward movements of which are effected by 85 the inner plunger, substantially as described.

3. In a force pump the combination with a cylinder having inlet and outlet ports, of a pair of plungers reciprocable therein, a crank shaft and crank, connections from the crank to one of said plungers, having a part, extending through the other plunger, and provided with means for engaging and moving the latter plunger in one direction, its movement in the opposite direction being effected by the crank actuated plunger and means operable in timed relation with the crank shaft for holding the second mentioned plunger stationary during portions of the reciprocating movements of the first 100 mentioned plunger.

4. In a force pump the combination with a cylinder having inlet and outlet ports of a pair of plungers reciprocable therein, a crank shaft and crank for operating both 105 plungers, connections from said crank to one plunger provided with a part extending through and having a sliding engagement with the other plunger, and provided with means for positively operating the latter 110 plunger in one direction, its movement in the opposite direction being effected by the crank actuated plunger, a cam on the crank shaft provided with cam faces for holding the second mentioned plunger stationary 115 during a portion of the reciprocating movements of the first mentioned plunger in both directions and a part connected with the second mentioned plunger for operatively engaging said cam. 120

5. In a force pump the combination with a cylinder having inlet and outlet ports, of a pair of plungers reciprocable therein, a plunger rod connected to one of said plungers and extending through and having a 125 sliding engagement with the other plunger, said rod having a part for engaging and moving the latter plunger, a crank shaft and crank, said crank being operatively connected to said plunger rod, a cam on said 130

crank shaft provided with a pair of separated cam surfaces and a roller on said second mentioned plunger for engaging said cam surfaces to hold the said plunger stationary during portions of the movement of the other plunger in both directions.

6. In a force pump the combination with a cylinder having inlet and outlet ports, of a pair of plungers reciprocable therein, a plunger rod connected to one of said plungers and extending through and having a sliding engagement with the other plunger, said rod having a part for engaging and

moving the latter plunger, a crank shaft, and crank, a cross head secured to said plunger rod, and engaging a part connected with said crank, a rotary cam operated in timed relation with the crank shaft, and provided with two separated cam surfaces, and a friction roller connected with said second mentioned plunger for engaging said cam surfaces to hold the said plunger stationary during a portion of the movement of the first mentioned plunger in both directions.

MONTAGUE WILLIAM TUTT.
